UNITED STATES PATENT OFFICE.

EDMUND S. CHURCH, OF DAYTON, OHIO.

DRIVING MECHANISM.

1,099,116.

Specification of Letters Patent. Patented June 2, 1914.

Application filed February 12, 1908. Serial No. 415,885.

To all whom it may concern:

Be it known that I, EDMUND S. CHURCH, a citizen of the United States, residing at Dayton, in the county of Montgomery and State of Ohio, have invented certain new and useful Improvements in Driving Mechanism, of which I declare the following to be a full, clear, and exact description.

This invention relates to driving mechanisms and has among its main objects to provide an improvement in transmission devices whereby any desired ratio of transmission may be obtained without the use of change gears.

Another object is to provide a transmission mechanism adapted to work at any desired variable ratio and including air cushioning devices whereby all jar due to change in ratio or to change in speed of the prime mover is obviated.

A further object is to provide a transmission mechanism which will also serve as a fly wheel or governor for the prime mover thereby lessening the total weight and cost of the mechanism.

Another object is to simplify the universal ratio transmissions now in use to reduce the cost of the number of parts and to prevent frequent break-downs such as have been experienced.

With these and incidental objects in view the invention consists in certain novel features of construction and combinations of parts, the essential elements of which are set forth in appended claims and a preferred form of embodiment of which is hereinafter described with reference to the drawings which accompany and form part of this specification.

Of said drawings: Figure 1 is a side view of an automobile frame showing the invention applied thereto. Fig. 2 is a top plan of the parts shown in Fig. 1 in elevation but with a clutch mechanism shown in section. Fig. 3 is a vertical section through the transmission mechanism with some parts shown in elevation. Fig. 4 is a vertical section through the transmission mechanism and at right angles to the plane of Fig. 3. Fig. 5 is a detail of a connecting link.

The invention is shown in the drawings and will be described, as adapted to an automobile but it is to be understood and will be readily apparent that this is only one of many uses to which it may be applied.

The advantages of the present invention

may be gained by its use with any mechanism where it is desired to drive the same through some prime mover but at a varying ratio of reduction or increase of speed.

The invention comprises a cylinder or a plurality of cylinders having a piston or pistons which are connected through adjustable devices to a transmission shaft. The adjustable connections may be so varied as to change the leverage of the applied force on the cylinders, and at the same time this serves incidentally to change the stroke of the pistons and to thereby change the amount of compression of the fluid, usually air, which is in the cylinders and thereby to further vary the amount of power transmitted. This construction provides in effect a universal ratio transmission mechanism in as much as a simple movement of the adjustable parts determines the leverage exerted by the prime mover on the driven mechanism, that is, it produces the identical effect of the complicated change gearing constructions now employed. Besides the advantage of simplicity of construction of this universal ratio, there is produced the additional advantage that there is no jar produced in changing from one ratio of transmission to another, this being due to the air cushion mechanism employed. It is to be understood that any suitable compressible fluid may be used, air being chosen as the simplest. In fact it would serve to use any other yieldingly compressible medium, possessing a substantial amount of compressibility, intervening between the pistons and the cylinders, that is between the driving and the driven members. Air is selected as a preferable spring-compressible medium to transmit the power from the driving to the driven member.

It is particularly in this respect, that the device differs from one using an incompressible fluid, such as water, where complicated mechanisms must be employed for pumping greater or less amounts of water. Although the construction is not so shown herein, a simple and obvious reversal of parts will provide a mechanism wherein the inertia of the rotating parts of the transmission will serve as a fly-wheel for the prime mover thereby doing away with the unnecessary weight and cost of the regular fly-wheel.

As the construction is shown, the mechanism is adapted not only to transmit power, but to act as a brake by the simple moving of the clutch lever. When the mechanism

is driving, compression is produced in the cylinders and the power thus transmitted through the intervening compressed air medium serves to drive the machine. The stopping of the driving part of the device will cause the compression to still take place but in an opposite ratio and direction thereby producing a powerful braking effect. It is to be noted, moreover, that the braking effect is in precise ratio to the speed at which the machine is being driven and will therefore tend to stop the mechanism after a certain constant number of turns have been given or a certain constant distance has been covered.

Referring now to the drawings a specific description may be given of the parts, prefaced however, by a general statement of the automobile construction which is old in the art. The invention is applied to a four cylinder machine of a well known type but it will be understood that this is merely for purposes of illustration and that the invention may be applied to any form of automobile and in fact to entirely distinct types of mechanism. The engine cylinders 10 drive through a shaft 11, one member 12 of a disk clutch. Adapted to be forced into frictional contact with the member 12 is a movable member 13 moving between the part 12 of the clutch and a stationary complementary friction member 14, carried by the machine frame. The movable part 13 is splined on a transmission shaft 15 which is connected through the improved transmission mechanism, indicated in general by numeral 16, to the rear driving axle 17. A reversing lever 18 connected through a link 19 to a hand lever 20 may be the same as ordinarily employed in automobiles. The moving part 13 of the clutch is carried by a sleeve splined to the transmission shaft 15 so as to rotate therewith but to be permitted a slight longitudinal movement thereon. This longitudinal movement is provided by a collar 22 in a circular groove 23 in which a lever 24 operates, this lever being adapted to be moved by the foot of the passenger, so as to provide both a neutral position for the moving member 13 in which it will engage neither the driving member 12 nor the stationary member 14 and a rearward position in which it is positively forced against the rear member 14. The clutching action, that is, the contacting of the member 13 with the driving member 12 is produced by any usual spring 25 or other desired mechanism.

It was stated that the transmission mechanism was indicated by reference numeral 16 and its position relative to the rest of the mechanism will be seen from Figs. 1 and 2. It may be here stated, however, that this is not its only possible position and in fact many advantages may be obtained from placing it much nearer the clutch parts 65 whereby the fly-wheel effect may be pro-

duced by the transmission mechanism and its supporting casing.

Referring now to Figs. 3 and 4, the driving shaft 15 has mounted rigidly thereon a crank arm 31 to the distal end of which is pivoted a link 32 at a point 33. This link is provided with a laterally extending arm 34, best shown in Fig. 5, on a pin 36 carried by which are pivoted three piston rods 37 rigidly mounted to pistons 38 which reciprocate in cylinders 39. These cylinders are pivoted at 40 to the main casing 41 of the mechanism so as to rotate therewith but to be capable of an oscillation relative thereto. The link 32 is provided with a downwardly extending projection 41^a at the bottom of which is a pin carrying an anti-friction roller 42 riding in a cam groove 43 on a box cam 44 which normally rotates with the transmission shaft 15. The casing 41 is rigidly supported by and rotates a second transmission shaft 46 which as shown in Figs. 1 and 2 is connected in any desired or usual manner with the rear driving axle of the machine.

It will be readily seen that if the transmission shaft 15 is rotated by the engine or by any prime mover that an equal rotation of crank 31 will be produced. A pull of crank 31 on link 32 serves, in as much as the roller 42 is rigidly held in cam groove 43, to alternately compress and release the fluid in the cylinders 39 in succession. In the drawings three cylinders are shown but this is merely by way of illustration and any number of cylinders may be employed. Assuming the mechanism to be in the position of Fig. 3 and the shaft 15 being rotated the sectioned piston 38 will have compressed the air in cylinder 39 which will thereby drive the casing 41 and the transmission shaft 46. This driving force will become greater as the compression is increased until the mechanism is in such position that the piston rod 37 is in a direct radial line from the shaft 15 after which time further movement of shaft 15 will serve to lower the pressure in the sectioned cylinder 39 and to increase the pressure in the cylinder at the top of the figure. This operation will repeat itself in rapid succession and with the number of cylinders shown the driving effect is practically continuous.

It is to be noted that when the parts are in the position of Fig. 3 the highest compression in cylinder 39^a has already been produced and the fluid therein is expanding the direction of rotation being shown by arrows on Fig. 3. This would produce a back re-action on the casing 41 and consequently tend to rotate the casing 41 reversely. But with the parts as shown in Fig. 3, the compression in cylinder 39, balances that in 39^a. Therefore, if the driving pin 36 is at rest, these two compressions would stay balanced

just as if they were two oppositely acting springs, and there would be no resultant movement of the casing 41. But when the driving pin 36 moves in the direction shown by the arrow, this produces further compression in the cylinder 39, thereby transmitting further driving force to the casing 41 through this spring cushioning air, already compressed in cylinder 39. At the same time, the retreating of the driving pin 36 from the cylinder 39^a, allows the compressed air in the cylinder 39^a to expand. The result is of course, the transmission of the driving power from the pin 36 through the cylinder 39, or rather its inclosed compressed air, to the casing 41. Furthermore, as soon as the pin 36 begins to leave the dead center point for the upper or third cylinder, it then begins to compress the air within said cylinder and, likewise to transmit rotary driving force through said cylinder. It will be understood, that the real rotary driving force of the driving pin 36, is due to such position of the pin as to make its direction of applied power something other than a radial direction, that is, radial with reference to the casing 41. For example, when the pin 36 is off of the radial line between the shaft 15 and the pivotal point 40 of the cylinder, the driving push of the pin 36 on the cylinder pivot 40, may be resolved into a radial and a tangential force, the latter being the force which rotates the casing 41. This really amounts to getting a leverage on the casing 41, for the application of the driving power of pin 36. This leverage changes successively for each cylinder from minimum to maximum and back to minimum, whenever the pin 36 is traveling in a determined circular path at a fixed distance from the shaft 15; and furthermore, this leverage may be increased as will later be explained, by increasing the distance of the pin 36 from the shaft 15, that is, increasing the radius of its circular travel. It will be seen by studying the various effects at various parts of a turn that although the drive effect is not absolutely constant it is nevertheless approximately so, much more so than is the case with a single cylinder drive motor.

The previous description explains how the driving effect is produced but with the construction thus far disclosed only a constant ratio of transmission would be obtained. To provide the universal ratio before referred to is the object of the cam disk 44.

As shown in Fig. 1 a lever 51 is provided convenient to the operator and this is connected through any desired means, here shown as a shaft 52 and a crank arm 53 thereon, to a link 54 serving to oscillate a lever 55. The lever 55 at its outward end is provided with a roller or pin moving in a circular groove 57 of a collar 58 which is rigidly fastened on a sleeve 59 connected by

a spline 60 to the transmission shaft 15 so that the sleeve 59 may slide along the shaft 15 but must nevertheless rotate with it. Cut in sleeve 59 is a cylindrical cam groove 61 in which rides a pin 62 rigidly fastened to a longitudinal sleeve supporting the cam disk 44. From this description it will be clear that movement of the lever 51 will slide the sleeve 59 along the transmission shaft 15. Assuming that the transmission shaft 15 is stationary this longitudinal movement of sleeve 59 will clearly rotate the cam disk 44 through the cylindrical groove 61 and pin 62. It will be evident from Fig. 3 that rotation of cam 44 will cause the link 32 to approach or recede from the radial line of crank arm 31. In the position of Fig. 3 roller 42 is in the extreme outer part of groove 43 and the pivot point 36 is thereby at its greatest possible distance from the center of shaft 15. If cam disk 44 is rotated in a clockwise direction as seen in Fig. 3, the pivot point 36 will be gradually raised and when the roller 42 engages the other extreme end of the groove 43 which position is shown in dotted lines the pivot point 36 will be precisely in line with the shaft 15. In this last mentioned position of the parts no driving effect whatever is produced as no compression is given in the cylinders. In intermediate positions greater or less compression is produced in the cylinders and greater or less leverage of the driving force precisely in proportion to the distance from the line of shaft 15 which is given to pivot pin 36. It will be evident from this description that the mechanism performs the desired function of a universal ratio transmission in a very simple and at the same time very effective manner. The mere throwing of the lever 51 serves to position the pivot pin 36 at any point within its extreme range and thereby determines precisely the length of stroke of pistons 38 and consequently the compression produced in the cylinders and particularly changing the leverage applied by the driving power through the pin 36 upon the pivotal points of the cylinders, this increased leverage serving to transmit greater power to the driven casing 41.

The mechanism was described as if the parts were standing still but it will be evident that whether shaft 15 is rotating or standing still, movement of lever 51 will immediately cause the shift in position of pivot pin 36. The cam 44 is normally driven with the shaft 15 and with the same speed so that the pivot pin 36 will occupy a position stationary to cam 44 although the shaft may be rotated, at any desired speed. If the shaft is rotating, movement of lever 51 will cause the cam 44 to either advance or lose ground relative to the movement of shaft 15 and this relative movement will produce a shifting of the position of

pivot pin 36 and a consequent variation in the driving force produced. The valves 61^a, one of which is shown in each of the cylinders are merely for the purpose of letting in 5 any fluid which may be necessary to replace leakage past the pistons 38. It will be clear from the shape of the valves 61 that the compressing movement of pistons 38 will cause them to seat and to permit no escape 10 of fluid. In the case where air is used the exhausting movement of pistons 38 will if any air leaks past the piston serve to lower the pressure inside the compression cylinder to an amount lower than the usual at- 15 mospheric pressure when outside air will immediately enter through the valves 61. If a fluid other than air is employed some other equivalent mechanism would be necessary to counteract any leakage.

20 As the mechanism is shown, the transmitting shaft 15 is connected to the cylinder pistons and the cylinders are directly fastened to the second transmitting shaft 46, but it is to be noted that this mechanism is 25 entirely reversible and such reversal is considered to be within the present invention. Assuming that shaft 46 is the one driven from the prime mover it will be clear that the casing 41 and cylinders 39 will then be 30 rotated at a speed equal to that of the engine. If the pivot pin 36 is precisely in line with the shaft 15 which would then become the second transmitting shaft no effect will be produced, but if cam 44 is 35 moved to withdraw the pivot point 36 from the line of shaft 15 the movement of cylinders 39 will then cause compression of the fluid therein and produce a driving effect on the link 32 and crank 31 which may be 40 communicated to the driven mechanism. It will be evident that to cause this reversal absolutely no changes are necessary except possibly a mere change in the position of the mechanism. This second described form 45 has, moreover, some advantages over the first form among which may be mentioned the fact that the rotating casing 41 and the cylinders 39 mounted thereon will produce a very decided fly-wheel effect in the prime 50 mover. In fact the combined weight of the mechanism might be made practically enough to do away with the necessity of the usual fly-wheel entirely. In such a construction the casing 41 would be moved from 55 the position of the figures in directly in the rear of the clutch and possibly some supporting piece from the side frame of the machine would be advisable. This reversal as above stated is distinctly within the present 60 invention and the claims herein are not to be limited to the present form.

The clutch mechanism was described as a combined clutching and braking device and it will be seen that this braking action also 65 depends on the transmission cylinders and

the connected parts. With the moving member 13 in the position of Fig. 2, the ordinary clutch action is produced but if pedal lever 24 is used the moving member 13 may be engaged with the stationary member 14 thereby stopping movement of the transmitting shaft 15. When the shaft 15 is stopped thus, it does not serve to immediately stop the shaft 46 but it does immediately reverse the action of the cylinders 39 and connected parts. If the crank 31 is stationary as would be the case under the described conditions the cylinders 39 then rotate, due to the inertia of the moving mechanism and a very decided braking effect is produced due to the compression in the cylinders. It is, moreover, to be noted that this braking effect is higher the faster the cylinders are running and has in reality precisely a direct ratio to their speed of movement. It therefore follows, that the faster the machine is running the greater will be the braking effect so that the machine will be stopped in nearly the same time or distance no matter at what speed it was running. It will be noted that 90 the braking action when shaft 15 is the driving shaft is identical with the driving action when shaft 46 is the driving shaft, so that the braking action really provides the reversal of operation which was above referred to. The braking effect may evidently be increased or diminished by movement of the cam 44 in precisely the same way as the drive effect is increased or diminished so that although the mechanism will have a 95 braking effect proportional to its speed under normal conditions, the braking effect may nevertheless be increased or diminished at will by a simple movement of lever 51.

Many advantages of the mechanism have 100 been referred to in the description, and it will be evident that the transmission is much simpler than that usually employed consisting of shifting gears and is less liable to break down. The parts are few in number 105 and of simple construction so that they may be cheaply and easily made and readily assembled. The advantages of the universal ratio are obtained and at the same time the great advantage of lack of jar in shifting 110 from one gear to another is entirely obviated as the change may be as gradual as desired.

The means preferred for varying the compression in the cylinder may be changed and many other forms used without avoiding the 115 invention as the invention is not considered to reside in the particular form employed but to include any means whereby the machine is driven through an air cushion with means for varying the amount of compression or compression effect in the device. It 120 is to be understood therefore, that the claims including this part of the mechanism are to be broadly construed except where limited by the prior art.

What is claimed is as follows:

1. In a driving mechanism, the combination with a power transmission shaft, of a plurality of cylinders having pistons therein, a second transmission shaft and means carried thereby for pivotally supporting said cylinders, a crank rigid on said first shaft, a link connecting the distal end of said crank to said pistons, a hand operated device for 10 swinging the link around the distal end of said crank to vary the radial distance of said piston connections from the first shaft, and a mechanism driven from one of said shafts.
- 15 2. In a driving mechanism, the combination with a power transmission shaft, of a plurality of cylinders having pistons therein, a second transmission shaft and means carried by said second shaft for pivotally 20 supporting said cylinders, a crank on said first shaft, a link pivoted to said pistons and to the distal end of said crank, a cam carried by and moved normally with said first shaft but capable of movement relative to said 25 shaft, connections whereby the relative movement of said cam serves to vary the position of the pivotal connection between said link and said pistons relative to said first shaft, a hand operated device for giving 30 the said cam its movement relative to the first shaft, a prime mover for driving one of said transmission shafts, and a mechanism driven by the other of said shafts.
- 35 3. In a driving mechanism, the combination with a driving member, of a plurality of compression cylinders each having a piston and constructed to confine a body of air ahead of the piston, connections between said driving member and pistons, and means 40 for varying the position of said connections relative to said driving member and to said cylinders in a direction to increase or decrease the leverage of the driving member on said cylinders, and mechanism connected 45 to and driven from said cylinders.
4. In a driving mechanism, the combination with a power transmitting shaft, of a plurality of cylinders each having a piston and constructed to confine a body of air 50 ahead of the piston, a carrier upon which said cylinders are mounted, with connec-
- tions between said carrier and a driven member; a common piston connection between said power shaft and said plurality of pistons; and manipulative means for changing 55 the position of said common piston connection to vary the leverage transmitted by the power shaft to the cylinders and to the driven member.
5. In a driving mechanism, the combination with a power shaft, of a driven shaft, a rotary carrier connected with said driven shaft; a plurality of cylinders mounted circumferentially on said carrier, each of said cylinders being constructed to confine a 60 body of air ahead of its piston; a common operating connection to which the cylinder pistons are all united; connections between the power shaft and said common operating connection for moving the latter in a circular path with reference to said cylinders and concentrically to said power shaft; and means for shifting the position of said common operating connection to increase or decrease the radius of its circular travel and 65 thereby to simultaneously increase and decrease both the leverage of the power shaft on the cylinders and the compression of the air there within.
- 70 6. In a driving mechanism, the combination with a driving member, of a plurality of power transmitting devices each of which comprises a primary and a secondary element co-acting with each other and an intervening elastic compressible medium; connections between the said driving member and each of said primary elements; means for varying the leverage position of said connections relative to said driving member and to said power transmitting devices in 75 a direction to increase or decrease the leverage of the driving member on said devices; and a driven mechanism connected to said secondary elements of said power transmitting devices.
